END LOUNGE GLIDER

Eustace C. Bowen, 5895 S. Telegraph, Taylor, Mich.
Filed Mar. 20, 1961, Ser. No. 96,779
2 Claims. (Cl. 297—273)

This invention relates to a novel and improved article of furniture, and more particularly to a novel end lounge glider.

It is an object of the present invention to provide an end lounge glider which comprises a base frame upon which is swingably mounted an upper frame adapted to carry the cushion on which the user may be disposed. The end lounge glider of the present invention further includes a hand puller device which is fixedly connected to the fixed base frame and which extends upwardly adjacent one side of the upper movable frame, whereby the user may move the upper frame in a forward and rearward motion by exerting a slight hand pressure on the hand puller.

It is another object of the present invention to provide an improved end lounge glider which is economical of manufacture, compact and simple in construction, efficient in operation and which is durable and is comprised of a minimum of working parts.

It is a further object of the present invention to provide an end lounge glider which includes a lower base frame and an upwardly disposed movable handle pushing supporting frame, and wherein the frames are constructed from light-weight tubular members such as aluminum tubing or the like.

It is still another object of the present invention to provide a novel and improved end lounge glider which may be quickly and easily assembled for use and easily and quickly disassembled for storage purposes.

Other objects, features and advantages of this invention will be apparent from the following detailed description and appended claims, reference being made to the accompanying drawings forming a part of the specification wherein like reference numerals designate corresponding parts of the several views.

In the drawings:

FIG. 1 is a side elevational view of an end lounge glider made in accordance with the principles of the invention;

FIG. 2 is a top plan view of the structure illustrated in FIG. 1;

FIG. 3 is an end elevational view, taken along the line 3—3 thereof of FIG. 1 and looking in the direction of the arrows;

FIG. 4 is an enlarged fragmentary side elevational view of the structure illustrated in FIG. 2, taken along the line 4—4 thereof and looking in the direction of the arrows;

FIG. 5 is an enlarged fragmentary elevational sectional view of the structure illustrated in FIG. 4, looking in the direction of the arrows 5—5;

FIG. 6 is an enlarged elevational sectional view of the structure illustrated in FIG. 1, taken along the line 6—6 thereof and looking in the direction of the arrows;

FIG. 7 is an enlarged fragmentary elevational view of the structure illustrated in FIG. 2, taken along the line 7—7 thereof and looking in the direction of the arrows;

FIG. 8 is an enlarged fragmentary, broken horizontal sectional view of the structure illustrated in FIG. 2, taken along the line 8—8 thereof and looking in the direction of the arrows; and,

FIG. 9 is a fragmentary enlarged elevational sectional view of the structure illustrated in FIG. 2, taken along the line 9—9 thereof and looking in the direction of the arrows.

Referring now to the drawings, and in particular to

2

FIGS. 1, 2 and 3, wherein is shown an illustrative embodiment, the numeral 10 generally indicates a lower or base frame which is adapted to rest on the ground and be fixed in position. The numeral 11 generally indicates an upper movable frame which is swingably mounted on the base frame 10 for forward and backward movement, as more fully described hereinafter.

The base frame 10 comprises a right side vertical portion and a left side vertical portion which are interconnected by an upper horizontal portion. The right side portion will be described in detail with reference numerals applied to the various parts and similar reference numerals will be applied to the left side frame portion followed by the small letter "a." As shown in FIG. 1, the right side vertical portion of the base frame comprises the front leg 12 which slopes forwardly and downwardly into engagement with the ground, and which is integrally connected to a longitudinally disposed horizontal connector tube 13. As shown in FIGS. 1 and 2, the lower end of the front leg 12 is integrally connected to the rearwardly extended integral foot portion 14 which is in turn integrally connected to the transversely extended connector tube 15. As shown in FIG. 2, the inner ends of the transverse connector tubes 15 and 15a are detachably connected by means of a suitable coupling generally indicated by the numeral 16 and more fully described hereinafter.

As shown in FIG. 1, the right side portion of the base frame 10 further includes the intermediate U-shaped leg member which comprises a front leg 17 that is integrally connected at its upper end thereof to the horizontal connector member 13 and which is integrally connected at the lower end thereof to the horizontal foot tube or ground engaging member 18. The foot tube 18 is integrally connected at the rear end thereof to the upwardly and rearwardly sloping leg 19 which is integrally connected to the upwardly disposed horizontal connector tube 20, at the upper end of the leg 19. The horizontal connector tube 20 is integrally connected at the rear end thereof to the tubular leg 21 which extends downwardly and slopes rearwardly and is connected at the lower end thereof to the ground engaging tubular member 22. As shown in FIG. 1, the tubular member 22 engages the ground at the forward end thereof over a length of approximately seven inches, and the rear portion thereof extends slightly upwardly above the ground level. The rear end of the ground engaging member 22 is integrally connected to the upwardly and rearwardly sloping tubular connector member 23 which connects at its upper end to the horizontal rearwardly extended wheel carrying member 24. As shown in FIG. 1, the tubular member 24 is integrally connected to the lower end of the upwardly and forwardly sloping tubular leg 25 which is integrally connected at its upper end to the horizontal longitudinally extended connector tube 26. It will be seen that the tubular members 21 through 26 form what may be termed a rear substantially U-shaped ground engaging leg member.

As shown in FIGS. 1, 2, 3 and 9, the end lounge glider of the present invention is provided with a pair of wheels indicated by the numerals 27 and 28, for transporting the glider in a quick and easy manner. The wheels 27 and 28 are operatively mounted on the transverse shaft 29, the ends of which extend through suitable holes in the horizontal wheel carrying tubes 24 and 24a. The ends of the shaft 29 are threaded and have suitably mounted thereon the lock nuts 30 and 31. As shown in FIG. 9, the wheel 27 is provided with the bearing hubs 32 and 33 and is held in place against the tubing 24 by any suitable means, as by means of a conventional C-washer 34 mounted in a suitable groove in the shaft 29, as indicated by the numeral 35. The C-washer 34 may be of any suit-

able conventional snap ring type. The wheel 28 is provided with similar hubs and is held in place on the shaft 29 by a similar C-shaped snap ring construction. The wheels 27 and 28 are of a size commensurate with the height off of the ground of the tube 24 so as to provide a clearance of approximately one inch below the lower end of the wheels and the ground when the glider is in the position shown in FIG. 1.

It will be seen that the glider may be quickly and easily moved from place to place by merely grasping the front legs 12 and 12a and lifting upwardly, whereby the glider wheels 27 and 28 will engage the ground and the glider may be quickly moved to any desired place.

The horizontal portion of the base frame which interconnects the spaced apart vertically disposed right and left side frame portions comprises the longitudinally disposed horizontal tubes 36 and 37 which terminate at the front ends thereof at a point adjacent the front end of the horizontal connector members 13 and 13a as shown in FIG. 1. The longitudinal extended tubing or rail 36 is detachably connected to the horizontal connector members 13, 20 and 26 by any suitable means, as by means of the bolts and nuts generally indicated by the numerals 38, 39 and 40, respectively. As shown in FIG. 2, the other longitudinally extended tube 37 is also connected to the horizontal connector tubes 13a, 20a and 26a by similar bolts and nuts generally indicated by the numerals 41, 42 and 43, respectively. As shown in FIGS. 1, 2 and 3, the longitudinally extended frame rails 36 and 37 are provided at the rear end thereof with an integral transversely extended or cross tube portion 44 and 45, respectively, which are detachably connected at their inner ends by means of a coupling generally indicated by the numeral 46, and more fully explained hereinafter.

The tubing used in forming the lower or base frame 10 may be any suitable light-weight tubing as, for example, a one inch diameter aluminum tubing. As shown in FIG. 2, the longitudinal rails 36 and 37 of the base frame are interconnected by the detachably mounted cross shafts 47, 48 and 49. The shafts 47, 48 and 49 are suitably secured in place by any suitable means, as by suitable lock nuts, and these shafts are preferably approximately one-half inch in diameter. The side portions of the lower or base frame 10 are vertically spaced apart at a distance of approximately two and one-half feet.

The upper or movable frame comprises the spaced apart longitudinally extended tubes or rails 148 and 149, and they are spaced outwardly from the rails 36 and 37 approximately two and one-half inches. As shown in FIG. 2, the longitudinal rails 148 and 149 have integrally formed at the front ends thereof the transversely extended cross tubes 50 and 51 which are detachably connected at the inner ends thereof by the coupling generally indicated by the numeral 52. The coupling 52 is of the same construction as the couplings 16 and 46 and an enlarged detailed construction of this type coupling is shown in FIG. 7. The coupling 52 comprises the tubular member or sleeve 53 which is adapted to slidably receive the inner ends of the cross tubes 50 and 51. As shown in FIG. 7, the inner end of the tube 50 is welded in place in the sleeve 53 while the inner end of the tube 51 is detachably secured therein by means of the lock screw 54. It will be seen that the coupling 53 permits the tube portions 51 and 50 to be quickly and easily disconnected.

The upper frame 11 comprises a pair of spaced apart vertical side portions which extend downwardly from the rails 148 and 149 in spaced relationship from the lower frame 10. The right side vertical portion of the upper frame 11 will be described in detail and the left side will be marked with similar reference numerals followed by the small letter "b" since it is identical in construction. As shown in FIG. 1, the upper frame right side vertical portion comprises a front and rear longitudinally spaced apart, downwardly extended, U-shaped suspension leg generally indicated by the numerals 55 and 56. The front U-shaped leg or suspension member 55 comprises the

horizontal lower bight portion 57, the front end of which is integrally connected to the upwardly and forwardly sloping tubing 58 which is in turn connected integrally at the upper end thereof to the horizontal longitudinally forwardly extended tube 59. The front suspension leg 55 further includes the upwardly and rearwardly sloping tube 60 which is integrally connected at the lower end thereof to the horizontal portion 57, and which is connected at the upper end thereof with the longitudinally extended horizontal connector tube 61. The rear end of the connector tube 61 is integrally connected to the front vertical tube of the rear suspension leg 56, and the front tube is indicated by the numeral 62 and it extends rearwardly and downwardly and is integrally connected at the lower end thereof with the horizontal bight portion or tube 63. The tube 63 is integrally connected at the rear end thereof with the upwardly and rearwardly tapered tube 64 which is in turn integrally connected at the upper end thereof to the horizontal longitudinally disposed connector tube 65. As shown in FIG. 1, the longitudinal rail 148 is fixedly connected to the connector tubes 59, 61 and 65 by any suitable means, as by the bolts and nuts generally indicated by the numerals 66, 67 and 68, respectively.

As shown in FIG. 2, the longitudinal rails 148 and 149 of the upper frame are further interconnected by the longitudinally centrally disposed cross shaft 69 which would be provided with a downward curvature so as not to interfere with a cushion seated on the upper frame. As shown in FIG. 2, the upper frame is provided with a plurality of longitudinally spaced apart transversely disposed cushion supporting metal straps 70, the outer ends of which are connected to the rails 148 and 149. As shown in FIG. 8, one end of each of the cushion supporting metal straps 70 is connected by a suitable spring as 71 to the rail 148, and the other end thereof is connected to the rail 149 by a suitable connecting metal member 72.

The upper cushion supporting frame 11 is operatively supported in an elevated position approximately two and one-half inches above the rails 36 and 37 of the base frame by means of the following described structure. As shown in FIGS. 1, 2 and 3, the front end of the upper frame 11 is swingably supported on the base frame 10 by means of the steel straps 73 and 74. The upper ends of the steel straps 73 and 74 are swingably connected on the cross shaft 49 on the inside of the longitudinal rails 36 and 37. The lower ends of the straps 73 and 74 are offset outwardly and are swingably connected to a cross shaft 75 which is suitably secured through the horizontal portions 57 and 57b of the upper frame 11. The straps 73 and 74 are preferably steel straps about one inch in width. As shown in FIG. 1, the rear end of the upper frame 11 is swingably mounted by similar suspension straps indicated by the numerals 76 and 77 from the right side thereof, and by a pair of similar straps 78 and 79 on the left side thereof. The upper ends of the suspension straps 76 through 79 are swingably mounted on the cross shafts 47 and 48 of the base frame 10. The lower ends of the last mentioned straps are suitably swingably mounted on the cross shafts 80 and 81 of the upper frame 11, and these shafts are interconnected between the horizontal tubes 63 and 63a. The cross shafts 80 and 81 are secured in place by any suitable means, as by suitable lock nuts as 82.

As shown in FIGS. 1, 2, 3 and 4, the glider is provided with a right and left hand arm rest and these arm rests are identically constructed, and the description of the right hand arm rest will be given in detail and the left hand arm rest will be marked with similar reference numerals followed by the small letter "c." The right arm rest comprises the first tubing 83 which is spaced upwardly from the frame rail 148 and extends longitudinally thereof and slopes downwardly and forwardly. The front end 84 of the tube 83 is turned downwardly at right angles to the rail 148 and is fixedly secured thereto by any suitable means, as by the bolt and nut assembly 85.

The rear end 86 of the arm rest tube 83 curves backwardly and downwardly and is secured to the longitudinal tube 148 by means of the cross shaft 87. The right arm rest further includes the second longitudinally disposed tube 88, the forward end of which is connected to the tube 83 by means of the nut and bolt assembly 89, and the rear end of which is connected by the bolt and nut assembly 90 to the tube 83.

The glider is provided with a hand puller generally indicated by the numerals 91, and as shown in FIGS. 1, 2, 4 and 6. The hand puller comprises the lower U-shaped member 92 which is secured on the shaft 148 and to which is integrally connected the strap 93 that extends outwardly and around the longitudinal rail 148. Integrally connected to the part 93 is the upwardly extended strap 94 which is integrally connected to the inwardly turned handle member 95. It will be seen that the hand puller 91 is fixedly connected to the lower frame 10 and that a slight hand pressure on the same will move the upper frame 11 backwardly and forwardly.

The glider is provided with a back rest generally indicated by the numeral 96 and which comprises the two side vertical tubes 97 and 98 which are integrally connected at the upper end thereof by the transverse tube 99. The lower ends of the tubes 97 and 98 are suitably pivotally mounted on the cross shaft 87. It will be seen that the head rest 96 may be elevated from the dotted line position shown in FIG. 1 by the numeral 100 to the solid line position shown therein. The head rest 96 may be held in any suitable adjusted position by means of the cross bar 101 which is adapted to be adjustably mounted in the various slots as 102 formed in the plates as 103. The plates 103 are mounted in each of the arm rest members and are fixedly secured in place by any suitable means as by welding. A strip of material as 104 may be welded across the front face of the slots 102 to prevent the cross rod 101 from moving forwardly out of the member 103. The head rest is provided with suitable cross members 105 which are constructed the same as the cross straps 70 for supporting the head rest cushion thereon.

It will be seen that the user may dispose any suitable cushion on top of the movable upper frame 11 and also dispose a suitable head rest cushion on top of the head rest member 96. Experience has shown that a glider of this type is one which is rugged and endurable in construction and provides enjoyable relaxation.

While it will be apparent that the preferred embodiment of the invention herein disclosed is well calculated to fulfill the objects above stated, it will be appreciated that the invention is susceptible to modification, varia-

tion and change without departing from the proper scope or fair meaning of the subjoined claims.

What I claim is:

1. An end lounge glider, comprising: an elongated base frame adapted to rest on the ground; said base frame comprising a horizontal portion, and a pair of ground engaging vertical side portions connected to the horizontal portion at the sides thereof; an upper cushion supporting frame disposed over and enclosing said first named frame; said upper frame comprising a horizontal portion and a pair of vertical side portions connected to the horizontal portion at the sides thereof; the horizontal portion of the upper frame being disposed over the horizontal portion of the base frame, and the vertical side portions of the upper frame being disposed along the outer sides of the side portions of the base frame; means for movably mounting said upper frame on said first named frame; and, means fixed on said first named frame and connected to the upper frame for gripping by a user of the glider for moving the upper frame longitudinally of the first named frame in a forwardly and backwardly manner.
2. An end lounge glider, comprising: an elongated base frame including a horizontal portion and a pair of ground engaging vertical side portions connected to the horizontal portion at the sides thereof; an upper cushion supporting frame disposed over and enclosing said base frame in telescopic relationship; said upper frame comprising a horizontal portion disposed over the horizontal portion of the base frame in spaced apart relationship, and a pair of vertical side portions connected to the horizontal portion of the upper frame at the sides thereof and disposed along the outer sides of the side portions of the base frame in spaced apart relationship; means connected at the lower end thereof to the lower ends of the upper frame side portions and at the upper end thereof to the horizontal portion of the base frame for swingably mounting the upper frame on said base frame; and, means fixed on said base frame and connected to the upper frame for gripping by a user of the glider for moving the upper frame longitudinally of the base frame in a forward and backward manner.
